UNITED STATES PATENT OFFICE.

WILLIAM J. PATTERSON, OF BEAVER, PENNSYLVANIA.

DESIGN FOR A LAMP.

SPECIFICATION forming part of Design No. 14,821, dated February 26, 1884.

Application filed January 15, 1884. Term of patent 7 years.

To all whom it may concern:

Be it known that I, WILLIAM J. PATTERSON, of Beaver, in the county of Beaver and State of Pennsylvania, have invented and produced 5 a new and original Design for a Lamp, of which the following is a full, clear, and exact description.

This invention relates to lamps of cylindrical form in their general contour; and it consists in an ornamental configuration of the base and upper portion of the cylinder or body of the lamp, and of handles on opposite sides of said cylinder.

Reference is to be had to the accompanying 15 drawings, forming part of this specification, in which similar letters of reference indicate corresponding parts in both the figures.

Figures 1 and 2 represent elevations, as viewed at right angles with each other, of a 20 lamp having my new design.

The main or central portion, *b*, of the lamp-cylinder is straight, ornamented on opposite sides with handles *B*, of general rectangular shape in their transverse section, and each of 25 which, as seen from its opposite sides, consists of a straight upright stem portion, *c*, parallel with the portion *b* of the cylinder, and having horizontal arms or projections *dd* above and below, shaped to give each handle the 30 appearance of a double or upright and inverted cross, the inner arms of which are longer than the outer ones, and said sides of each handle being further ornamented with a partly-round bead, *e*, in central relation with the stem *c* and arms *dd*, and of like configuration in direction of their length with the 35 double or inverted-cross shape of the body portion or stem *c* and arms *dd* of each handle.

The main or central portion, *b*, of the cylinder is ornamented by a base of cylindrical 40 contour, and composed of two rounded moldings or beads, *ff*; arranged above a combined fillet and ovolo molding, *g*, beneath which are two separated rounded moldings, *h h*, united by a bevel, *i*, all mounted upon a base molding, *k*, of straight cylindrical contour, having 45 its upper edge rounded.

The upper part of the main or central portion, *b*, of the lamp-cylinder is ornamented by two rounded moldings, *ll*, a fillet, *m*, and convex-shaped top *n*.

I claim—

1. The within-described design for a lamp cylinder or body, consisting of a straight cylindrical main or central portion, *b*, ornamented at its base by the circular moldings *ff*, *g*, *h h*, *i*, and *k*, substantially as shown in the accompanying drawings.

2. The within-described design for a lamp cylinder or body, consisting of a straight cylindrical main or central portion, *b*, ornamented on its top by double rounded beads or moldings *ll*, a fillet, *m*, and convex upper portions, *n*, all of circular form, as shown.

3. The within-described design for a lamp cylinder or body, consisting of a straight cylindrical main or central portion, *b*, ornamented on opposite sides by handles *B B*, of a double or upright and inverted-cross configuration, having a bead or molding, *e*, on their sides or 70 faces, substantially as shown in the drawings.

WILLIAM J. PATTERSON.
